UNITED STATES PATENT OFFICE

150,071

DESIGN FOR A MEDALLION OR SIMILAR ARTICLE

Thomas H. Jones, Washington, D. C., assignor to the United States of America as represented by the Secretary of the Army

Application January 26, 1948, Serial No. 144,022

Term of patent 14 years

(Cl. D29—19)

To all whom it may concern:

Be it known that I, Thomas H. Jones, a citizen of the United States and resident of the city of Washington, in the District of Columbia, have invented a new, original, and ornamental Design for a Medallion or Similar Article, of which the following is a specification, reference being had to the accompanying drawings, forming a part thereof.

Fig. 1 is a front view of a medallion showing my new design.

Fig. 2 is a side view of the same.

It is understood that my design may be embodied in such articles as a medal, badge, plaque, or sign, without departing from the spirit of my invention.

The essential features of my design are shown in full lines.

I claim:

The ornamental design for a medallion or similar article, as shown and described.

THOMAS H. JONES.
